UNITED STATES PATENT OFFICE.

HERBERT J. HOPE, OF SANFORD, MAINE.

PILE-FABRIC LOOM.

1,295,898.

Specification of Letters Patent.

Patented Mar. 4, 1919.

Application filed August 31, 1917. Serial No. 189,053.

To all whom it may concern:

Be it known that I, HERBERT J. HOPE, a citizen of the United States, residing at Sanford, county of York, State of Maine, have invented an Improvement in Pile-Fabric Looms, of which the following description, in connection with the accompanying drawing, is a specification, like characters on the drawing representing like parts.

10 This invention relates to pile fabric looms of the type in which the pile is formed over a pile wire. In pile fabric looms of this type, the shuttle box on the side of the loom upon which the wire motion is located is frequently sustained on a movable support which is actuated by suitable devices to move it relative to the lay as the latter vibrates, the purpose of this construction being to cause the shuttle box to be moved rearwardly relative to the lay when the latter beats up so that the shuttle box will beat up out of the way of the wire motion. The present invention relates to means for thus moving the shuttle box relative to the lay and has for its 25 object to provide a novel mechanism for this purpose which is capable of high speed operation and which will invariably position the shuttle box correctly for the shuttle to be picked when the lay is in its rearward position and will positively move the shuttle box out of the way of the wire motion when the lay beats forward, and which will have other advantages, all as more fully set forth hereinafter.

30 35 In order to give an understanding of my invention, I have illustrated in the drawing a selected embodiment thereof which will now be described, after which the novel features will be pointed out in the appended claim.

Figure 1 is a side view of a portion of a loom frame showing a portion of the lay and the shuttle box and also illustrating my improved shuttle-box-controlling mechanism, said figure showing the lay in its rearward position with the shuttle-box in proper position to have the shuttle picked through the shed;

40 45 Fig. 2 is a similar view showing the relative position of the parts when the lay is in its forward position. In Figs. 1 and 2 the frame for supporting the rock-shaft of the shuttle-box-controlling mechanism is omitted;

50 55 Fig. 3 is a plan view.

I have illustrated in the drawings only a

sufficient portion of a loom to permit my invention to be understood.

1 indicates a portion of the loom frame in which is journaled the crank shaft 2 from which the lay 3 is operated, said lay being connected to the crank shaft by the usual connecting rods 4. The lay is sustained on the usual lay-swords 5 which are mounted on the rock-shaft 6 journaled in the loom frame. 60 The lay 3 carries the usual reed which, however, has been omitted from the drawings in order to simplify the illustration. Neither have I attempted to show the complete wire motion as this may be of any 70 usual construction, but I have simply illustrated at 8 a portion of the wire-bar or guide in which the pile wires are guided as they are inserted into or removed from the fabric, said wire-bar being sustained on the portion 9 of the frame. 75

7 indicates the shuttle box which is on that side of the loom upon which the wire motion is located, said shuttle box being mounted for fore-and-aft movement relative to the lay as usual in pile fabric looms of this type, so that when the lay is at the rearward end of its stroke, the shuttle box may be properly positioned to have the shuttle picked through the shed, while when the lay 85 is at the forward end of its stroke, the shuttle box may be moved rearwardly relative to the lay so that it will not interfere with the wire motion.

I have provided herein a simple mechanism for thus controlling the position of the shuttle box 7 relative to the lay by which the shuttle box is positively held in its proper position at all times. The shuttle box 7 is shown as supported on an arm or support 90 10 which is pivotally mounted on the rocker 6, said support 10 being capable of swinging movement about the rocker, thus to move the shuttle backward and forward relative to the lay 3. The lay is herein shown as having secured thereto a guiding member 11 95 having a guiding slot 12 therein in which operate the ends of guiding pins 13 carried by the shuttle box. 100

The lay 3 has one end of a link or connection 15 pivotally secured thereto at 14, the other end of said link being pivotally connected at 16 to an arm 17 fast on a rock-shaft 18 that is journaled in suitable bearings 19 sustained by the portion 9 of the loom frame. 110 The rock-shaft 18 thus receives an oscillatory or rocking movement from the back-

ward and forward movement of the lay. A suitable connection is provided between the rock-shaft 18 and the shuttle-box whereby such oscillatory movement of the rock-shaft 5 will cause the shuttle box to have a movement relative to the lay thereby to place said box in proper position for the shuttle to be picked through the shed when the lay is in its rearward position and to move the 10 shuttle box out of the way of the wire motion when the lay is in its forward position. The connections herein shown for this purpose comprise two arms 20 fast on the rock-shaft 18 and which are connected to the support 15 10 by means of two links or connecting members 21. The arms 20 are shorter than the arms 17, and as a result, the fore-and-aft movement of the connections 21 will be less in amplitude than that of the link or connection 15.

Fig. 1 shows the lay in its rearward position (which is the position it occupies when the shed is open) and the shuttle box in proper position to have the shuttle picked 25 through the shed. As the lay moves forward into the position shown in Fig. 2, the connection 15 will swing the arm 17 forwardly, thus turning the rock-shaft 18 clockwise, Figs. 1 and 2. This movement 30 of the rock-shaft will operate through the arms 20 and the links or connections 21 to move the supports 10 and the shuttle box 7 forwardly, but owing to the fact that the arms 20 are shorter than the arm 17, the 35 connections 21 will be moved at a slower speed than the connection 15 and will move through a lesser distance than said connection 15. During this forward movement of the lay, therefore, the shuttle box is moving 40 at a slower rate of speed than the lay so that when the lay reaches its forward position shown in Fig. 2, the shuttle box will only have traveled a portion of the distance that the lay has traveled and will be 45 located in the relative position shown in Fig. 2, in which position it is out of the way of the wire motion. When the lay is moved rearwardly again, the shuttle box will also be moved rearwardly, but at a 50 slower speed, and at the end of the rearward stroke, the shuttle box will be positively positioned in the position shown in Fig. 1 which is the correct position to have the shuttle picked through the shed. The 55 shuttle box thus derives its motion from the lay through positive connections which invariably maintain the shuttle box in the proper position at all times. There is, there-

fore, no possibility of the shuttle box becoming misplaced relative to the lay.

Since the shuttle-box-controlling mechanism is positive in its operation and does not depend upon cams or springs, it is possible to operate the loom at an increased rate of speed without danger of the shuttle-box becoming displaced. The device is, therefore, especially adapted for high speed operation.

I have shown herein adjustable connections between the link 15 and the arm 17 and also between the links 21 and the arms 20 so that the entire operating mechanism will be kept tight and free from back-lash or loose play.

The arm 17 is shown as having a block 22 pivotally connected thereto at 16, said block having an aperture through which the end of the connection 15 extends. The connection 15 is provided with two clamping nuts 23 by which the block 22 is firmly secured to the connection, said block thus constituting the means for pivotally connecting the link or connection 15 to the arm 17. Similarly, the rear end of each of the connections 21 extends through a block 24 which is pivoted to one of the arms 20 at 25, and each connection 21 is provided with two clamping nuts 26 which adjustably secure the block 24 to said connection. This construction not only provides for taking up all loose play and maintaining a tight connection between the lay and the supports 10, but also provides for adjusting the arms 17 and 20 relative to each other if such adjustment is necessary for the purpose of properly positioning the shuttle box at any point in the cycle of operations. The arms 17 and 20 are preferably adjustably secured to the rock-shaft 18 so that they can be adjusted angularly thereabout, said arms being maintained in the desired adjusted position by means of 100 set-screws 27.

I claim:

In a pile fabric loom, the combination with a loom frame, of a vibrating lay, and means to vibrate it, a swinging frame situated at 105 the end of the lay, a shuttle-box sustained on said frame, a rock-shaft journaled on the loom frame, a relatively long arm fast on said rock-shaft and connected to the lay, a pair of relatively short arms also fast on said rock-shaft, and a link connecting each of said relatively short arms directly to said swinging frame.

In testimony whereof I have signed my name to this specification.

HERBERT J. HOPE.
